GRAVY BOAT OR SIMILAR ARTICLE

Oscar W. Martha, Wallingford, Conn., assignor to R. Wallace & Sons Manufacturing Company, Wallingford, Conn., a corporation of Connecticut

Application April 4, 1955, Serial No. 35,341

Term of patent 14 years

(Cl. D44—10)

FIG. 1

FIG. 2

FIG. 4

FIG. 5

FIG. 3

Fig. 1 is a side elevational view of a gravy boat showing my new design;

Fig. 2 is a front elevational view thereof;

Fig. 3 is a top plan view thereof;

Fig. 4 is a cross-sectional view taken on lines 4—4 of Fig. 1; and

Fig. 5 is a cross-sectional view taken on lines 5—5 of Fig. 1.

I claim:

The ornamental design for a gravy boat or similar article, substantially as shown.
